UNITED STATES PATENT OFFICE

2,547,320

RADIUS GUIDE FOR CUTTING TORCHES

Herbert S. Hedley, Banning, Calif.

Application October 2, 1945, Serial No. 619,738

3 Claims. (Cl. 33—27)

1

My invention relates to cutting torches and has for an object to provide a guide for a torch through the use of which arcuate circular holes or arcs may be cut in metal in any position such as overhead, bulk-head, deck or otherwise positioned.

Another object of this invention is to provide a torch guide so formed that a circle may be cut and beveled in one operation.

Another object of my invention is to provide a torch guide having a center and means for adjustment of the guide relative to its work.

Other features and advantages will become more readily apparent from the following description and the accompanying illustrative drawings in which:

Figure 1 is a plan view of my torch guide, the center rod being in section,

Figure 2 is an elevational view of the device,

Figure 3 is a sectional view on line 3—3 of Figure 1.

Figure 4 is a detail sectional view of a torch holder,

Figure 5 is a perspective view of a radius rod guide, and

Figure 6 is a detail perspective view of a torch supporting and adjusting device.

In the accompanying drawings as above enumerated and in the following specification, like characters of reference indicate like parts throughout and in which 10, indicates my torch guide which consists of a spider-like support 11, provided with a series of right-angularly disposed arms 12, 13, 14 and 15, each being provided with a vertical bore 16, 17, 18 and 19, through which the screw ends 20, 21, 22 and 23, of bolts 24, 25, 26 and 27, are threaded and which form supporting legs for the spider, the heads 28 and 28' of the bolts forming feet for the device.

Vertically and adjustably mounted through the center of the spider is a rod or post 29, the lower end 30 of which is threaded and terminates in a center 31. Lock nuts 33, 34, and 35 are provided to lock the legs after adjustment thereof.

A spacer ring 36, seats around the rod 29, and is held fixed by a set screw 36', and a lock nut 37, is threaded on the rod above the spider to lock the rod in the smooth bore 38, through which the lower end 30, of the rod passes. Adjustably mounted on the rod 29, and rotatable thereon is one end 39, of a carrier arm 40, for a radius rod 41. The outer end 42, of said arm 40, is provided with a square slot 43, extending horizontally therethrough and through which

2

the radius rod is slidably adjustable and which may be secured in fixed position by a set screw 44. The member 40, is adjustably mounted upon the rod 29, through means of the spacer block 36, and the lock block 45, which is held in adjusted position on the rod by a set screw 46. A knob 47, is formed on the upper end 48, of the rod 29, by means of which a user may hold the device in operative position.

Pivottally connected to the end 50, of the radius rod 41, is a socket member 51, having an enlarged end 52, from which projects a pivot pin 53, which extends through aligning bores in a block 54 and radius rod 41. This block 54 has a slot 54', through which said end 50 of the radius rod 41 projects and is held thereto by a lock nut 56, on the threaded terminal 57 of the pin 53. A clinometer 58 is provided on the peripheral surface of the block 54, by means of which the member 51 may be set to a desired angle for a bevel cut presently to be referred to.

Seated within the socket 51, is the reduced end 59 of a collar 60, provided with a serrated or fluted inner surface 61 adapted to receive the torch head 63, which is held secured in the collar by means of set screws 64, 65. The cutting tip 66 of the torch head projects far enough beyond the collar to drive its flame upon the material to be cut.

In operation the radius rod 41, is set by means of its scale 67, and the index mark 68 on the upper surface 69 of the arm 40, to the half diameter of the circular cut to be made and then locked by set screw 44. The socket 51 is set by scale 58 to the bevel of cut desired and then locked by nut 56, and the center 31 will ordinarily be made to register with a punch mark on material to be operated on, the torch lighted and the device held in position by knob 47, and the cutting begun and continued by manually rotating the radius rod 41.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention, that which I claim as new and desire to procure by Letters Patent is:

1. A cutting torch guide comprising a spider

having a centering rod axially adjustably mounted thereon, a carrier arm axially adjustably and rotatably mounted on said rod above said spider, a sealed radius rod longitudinally adjustably mounted on said carrier arm, and a socket member adjustably mounted on said radius rod to hold a cutter torch tip at various angles, for cutting beveled edged circular holes in substantially flat sheet material, the radius rod being mounted transversely of said carrier arm and spaced from said centering rod a distance roughly corresponding to the distance of a cutter torch tip from the radius rod during operation of the cutter torch guide.

2. A cutting torch guide comprising a spider having a centering rod axially adjustably mounted thereon, a carrier arm axially adjustably and rotatably mounted on said rod above said spider, a sealed radius rod longitudinally adjustably mounted on said carrier arm, and a socket member adjustably mounted on said radius rod to hold a cutter torch tip at various angles, for cutting beveled edged circular holes in substantially flat sheet material, said spider having radially disposed arms and legs adjustably supporting said arms, the radius rod being mounted transversely of said carrier arm and spaced from said centering rod a distance roughly corresponding to the distance of a cutter torch tip from the radius rod during operation of the cutter torch guide.

3. A cutting torch guide comprising a spider having a centering rod axially adjustably mounted thereon, a carrier arm axially adjustably and

rotatably mounted on said rod above said spider, a sealed radius rod longitudinally adjustably and transversely mounted on said carrier arm, and a socket member adjustably mounted on said radius rod to hold a cutter torch tip at various angles, for cutting beveled edged circular holes in substantially flat sheet material, said spider having radially disposed arms and legs adjustably supporting said arms, and said centering rod being 10 threadedly secured on said spider and having an upwardly extending portion terminating in a knob to be used for steadyng the torch guide during operation thereof, the radius rod being mounted transversely of said carrier arm and spaced from said centering rod a distance roughly corresponding to the distance of a cutter torch tip from the radius rod during operation of the cutter torch guide.

HERBERT S. HEDLEY.
